J. HARTMAN.
ROLLER SKATE.
APPLICATION FILED MAY 27, 1916.

1,217,761.

Patented Feb. 27, 1917.

UNITED STATES PATENT OFFICE.

JOHN HARTMAN, OF BOZEMAN, MONTANA.

ROLLER-SKATE.

1,217,761.

Specification of Letters Patent. Patented Feb. 27, 1917.

Application filed May 27, 1916. Serial No. 100,246.

To all whom it may concern:

Be it known that I, JOHN HARTMAN, a citizen of the United States, residing at Bozeman, in the county of Gallatin and State of Montana, have invented new and useful Improvements in Roller-Skates, of which the following is a specification.

This invention relates to improvements in the construction of roller skates.

10 In carrying out my invention it is my purpose to produce a roller skate which shall be of an extremely simple, cheap and durable construction and which may be easily and quickly applied and firmly held 15 in position when applied.

Another object of the invention is to produce a roller skate wherein the wheels may revolve in a practically noiseless manner and also whereby the skate may be provided 20 with any desired number of wheels.

With the above and other objects in view the improvement resides in the construction, combination and arrangement of parts set forth in the following specification and falling 25 within the scope of the appended claims.

In the drawings:

Figure 1 is a view of a skate constructed in accordance with the present invention,

Fig. 2 is a sectional view approximately 30 on the line 2-2 of Fig. 1,

Fig. 3 is a sectional view approximately similar to Fig. 2 but showing the arrangement of the non-threaded axles, and

Fig. 4 is a substantially similar sectional 35 view showing the arrangement of a single axle which is not provided with the anti-frictional bearings.

The foot plate 1 of my improved skate, at the heel and toe portions thereof is provided 40 with downwardly extending bracket members 11 and 12 respectively which are arranged in spaced pairs and each of which is provided with an opening 13, and the outer face of each of the brackets is formed 45 with an annular flange 14 that surrounds the opening 13, and each of the said flanges is formed with an inner central continuous groove 14'. The flanges 14 are each provided with an orifice 15 which communicates 50 with the groove 14' in the said flange and which is normally closed by a removable plug 16. The axle for the front and rear wheels preferably comprises two substantially similar members which in the pre- 55 ferred form of the device are in the nature of bolts; that is, comprise members having

rounded shanks which are threaded, as at 15', and enlarged rounded heads 16 provided with kerfs 17 whereby the same may be rotated by a suitable instrument such as a screw driver. Each of the rounded heads 17 is provided with a continuous peripheral groove or channel 18, and these channels are adapted to receive anti-frictional bearings 19 which are passed through the orifices 15 in the flange of each of the bracket members and which contact with the angular side wall provided by the grooves 14'. The axle members 15' are adapted to be screwed in the threaded bore 60 of the hub member 20 of wheels 21. Each of the hubs is provided with a plurality of radially disposed spokes 22 having an integral rim 23. Within this rim is arranged a compressible tread 24, and the said 65 tread may be retained in the channel of the rim through the medium of binding elements 25 which pass through the said rim and contact with the said tread. As shown in the drawings the annular tread 24 may 70 have its inner face provided with a continuous rib 26 and the rim 23 may be centrally provided with a continuous channel 27 to receive the said rim.

In Fig. 3 of the drawings the construction is substantially similar to that just described but the shanks 29 of the axle members are smooth or non-threaded. The hub for the axles 29 has its bore smooth, the said hub being provided with binding elements, 85 such as screws 31 which contact with the said axles to secure the wheel 32 to the said axles.

In Fig. 4 of the drawings the axle 33 is in the nature of a rod which has its opposite ends centrally provided with threaded orifices to receive the shanks of threaded bolts 34, which also pass through caps 35 and force the said caps against the outer sides of the bracket members 11 and 12. 95 The hub for the axles is secured by the binding elements similar to the binding elements 31 whereby the wheels may be effectively connected with the axles.

Having thus described the invention, what I claim is:

1. A roller skate including a foot plate, said plate having depending brackets at the toe and heel portion thereof, each of said brackets having an opening and a groove 110 surrounding the opening, axles for the hubs, each axle comprising two similar members

each including a shank and a head and said heads having peripheral channels, the shank of each of the axles adapted to be passed through the opening in one of the brackets and to have its head received in the groove of the bracket, anti-frictional balls in the channels in the heads of the axles and contacting with the side walls of the grooves, and means, between the hubs of the wheels and the axles for sustaining the said axles in said hubs.

2. In a roller skate, a foot plate having depending brackets arranged in spaced pairs at the toe and heel portion thereof, said plate between the brackets being reinforced,

wheels, axles for the wheels, each of said axles comprising two similar members journaled in openings one in each of the brackets, said wheel including a flanged rim, a hub and spokes connecting the rim with the hub, 20 said hub adapted to receive the alining axle members, means between the hub and said axles for securing the axles to the hub, a flexible tread for each of the rims of each of the wheels, and means upon the rims co- 25 acting with the treads for sustaining the treads on the rims.

In testimony whereof I affix my signature.

JOHN HARTMAN.
